FIG. 3

INVENTOR

Carl Meyer.

By Owen Owen & Crampton,
Atlys.

UNITED STATES PATENT OFFICE.

CARL MEYER, OF TOLEDO, OHIO.

WRENCH.

1,390,371.

Specification of Letters Patent. Patented Sept. 13, 1921.

Application filed February 14, 1921. Serial No. 444,742.

To all whom it may concern:

Be it known that I, CARL MEYER, a citizen of the United States, and a resident of Toledo, in the county of Lucas and State of Ohio, have made an Invention Appertaining to Wrenches; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to wrenches, and particularly to those of the class for use in connection with threaded plugs or caps having notched or socketed wrench engaging ends, and has for its object the provision of 20 a simple, efficient and improved adjustable wrench of this character, which is easily and quickly operable to engage or release a plug or cap.

The invention is fully described in the following specification, and while, in its broader aspect, it is capable of embodiment in numerous forms, a preferred embodiment thereof is illustrated in the accompanying drawings, in which,—

30 Figure 1 is a central longitudinal section of a wrench embodying the invention in engagement with a cylinder plug. Fig. 2 is an outer end view of the body member of the wrench with the jaws removed, and 35 with a part broken away, and Fig. 3 is an end view of the plug engaging end of the wrench.

Referring to the drawings, 1 designates a cylinder of an internal combustion engine, 40 and 2 a plug screwed into an opening 3 therein. These plugs are sometimes provided at their outer ends with wrench receiving sockets, sometimes with notched wrench engaging flanges, and sometimes 45 with cross notches or recesses for receiving a turning member. It is the purpose of the invention to provide a wrench which is adapted for engagement with different forms of such plugs.

50 The wrench illustrated embodying the invention, comprises a body member 4 of cylindrical form, having at one end a squared portion 5 for facilitating engaging and turning the same with a wrench. The member 4 is provided with a threaded opening 6 axially therethrough for receiving a jaw

expanding screw 7, the inner end of which is provided with a tapered nose 8 for the purpose hereinafter described.

The body 4 is provided longitudinally 60 thereof in its sides, in equidistantly spaced relation therearound, with jaw receiving recesses 9, which preferably taper inward from the outer end of the body and open at their lower or inner end portions into the 65 threaded opening 6. These recesses, in the present instance, are four in number. A jaw 10 is mounted in each recess 9 for free movements radially therein, and has one end portion tapered to adapt it to substantially 70 fit the tapered portion of the recess 9, and has its other end portion provided at its inner side with an extension 11 projecting into the opening 6 in position to be engaged by the tapered nose 8 of the screw 7 so that 75 the jaws are relatively expanded or forced outward by an inward movement of the screw 7. The inner edges of the jaw extensions 11 are preferably of V form to adapt them to nest together in close relation within 80 the opening 6 when the jaws are in contracted position. The jaws are held to the body 4 and normally held retracted therein by a split spring collar or band 12, which is disposed in a peripheral groove 13 in the body 85 near its outer end and extends through registering recesses 14 in the jaws. The outer ends of the jaws 10 project beyond the inner end of the body 4 to adapt them to enter the socket or notches provided in the 90 outer end of the plug 2. The plug engaging ends of the jaws are preferably inwardly notched at their outer edges, as at 15, to adapt them to be inserted into a plug socket 95 which is of less diameter than the wrench body 4.

It is evident in the use of my wrench that the jaws 10 thereof when retracted may be quickly placed in engagement with the socketed or notched end of the plug 2 and 100 then radially expanded or adjusted to suit the size of the plug socket, such expansion being effected by an inward turning of the screw 7 with the tapered end 8 thereof in engagement with the inward extensions 11 105 of the jaws. When the wrench has been placed in turning engagement with a plug, a wrench may be engaged to the outer squared end 5 thereof to exert a turning pressure thereon. If the jaws 10 are inserted in a wrench receiving socket of a 110 plug an outward radial adjustment of the

2
jaws therein will cause them to firmly engage the side wall or flange of the socket so that the plug is retained in engagement with the wrench after its removal from a 5 cylinder or other member in which secured.

I wish it understood that my invention is not limited to any specific construction, arrangement or form of the parts, as it is capable of numerous modifications and changes 10 without departing from the spirit of the claims.

Having thus described my invention, what I claim as new, and desire to secure by Letters Patent, is,—

15 1. In a wrench of the class described, a cylindrical body member having an opening axially therethrough and a wrench gripping portion at its outer end and having a plurality of longitudinally extending recesses 20 in its sides opening at one end into the inner end portion of the axial opening, jaws mounted in said recesses for radial movement therein and having portions entering the axial opening of the member and end 25 portions extending beyond the inner end of the member in work engaging position, and a split spring ring encircling the body member and yieldingly holding the inner ends of the jaws to the body member to permit 30 swinging radial movements of the outer end portions of the jaws, said ring normally locking the jaws against removal from the body member, and a screw threaded into the member opening and having its inner end

in engagement with the jaws to effect a radial expansion thereof when the screw is turned inward. 35

2. In a wrench of the class described, a body member having an axial opening therethrough, a wrench engaging portion at its outer end, a circumferential recess near its outer end and longitudinally extending recesses in its sides with one end portion intersecting the circumferential recess, said longitudinally extending recesses gradually 45 deepening and opening at the deepened end into the inner end of the body member opening, a jaw disposed in each longitudinal recess for radial movements therein and having an extension entering the member opening and a cross recess in its outer side in register with the circumferential recess of the body member, each jaw having its outer end projecting beyond the inner end of the body member in article engaging position, 50 an expandible spring ring extending around the body member in the circumferential recess thereof and cross recesses of the jaws to yieldingly hold the jaws against expansion, and a screw threaded into the body 55 member opening from the outer end thereof and having a tapered inner end for coaction with the inward extensions of the jaws to impart outward radial movements thereto when the screw is turned in one direction. 60

In testimony whereof I have hereunto signed my name to this specification.

CARL MEYER.
